Harold D. Penney, ATTORNEY.

UNITED STATES PATENT OFFICE

DAVID TULLOCH, OF GARWOOD, NEW JERSEY, ASSIGNOR TO HENRY B. NEWHALL CORPORATION, OF GARWOOD, NEW JERSEY, A CORPORATION OF NEW JERSEY

METHOD AND APPARATUS FOR GALVANIZING

Application filed June 25, 1931. Serial No. 546,777.

This invention relates to machines and processes for removing excess molten metal from nuts, bolts, screws and other small articles being galvanized or otherwise coated, and more particularly to planetary machines and processes of the general type described in U. S. Patent No. 1,530,614, issued March 24, 1925 for method of metal coating, and U. S. Patent No. 1,662,537, issued March 13, 1928, to Henry W. Pleister.

In said patents, molten metal, thrown from the molten-metal-covered articles rotated in a perforated basket, is caught by a baffle surrounding the path of the basket; and the metal became lodged on various parts of the machine, so that it was necessary to stop the machine to pry off the metal.

One object of the present invention is to provide a machine whereby the above mentioned inconveniences are eliminated.

Another object is to provide means for preventing the cooling of the heated articles while they are being whirled in the basket.

Other objects of the invention are to improve generally the simplicity, economy and efficiency of such machines and methods and to provide a machine of this kind which is economical, durable and reliable in operation, and economical to manufacture.

Still other objects of the invention will appear as the description proceeds; and while herein details of the invention are described and claimed, the invention is not limited to these, since many and various changes may be made without departing from the scope of the invention as claimed in the broader claims.

The inventive features for the accomplishment of these and other objects are shown herein in connection with an improved apparatus for removing excess molten metal from articles, said apparatus comprising means for imparting planetary movement to a table carrying standards on the margin of said table, between which standards is received a removable drum carrying perforated brackets received on the standards. A cover on the drum is provided with a large central opening and brackets receiving the standards and carrying releasable means engaging the

standards to hold the cover and drum in place. A cage is secured on the under face of said cover under said large opening and is adapted to receive a perforated basket of the molten-metal-covered articles disposable entirely within said cage, to be held therein by a removable closure held over said large opening and basket.

In the accompanying drawing showing, by way of example, one of many possible embodiments of the invention,

Fig. 1 is a fragmental side elevation of the machine;

Fig. 2 is a plan showing the drum cover and closure, and the table;

Fig. 3 is a fragmental vertical sectional view, partly in elevation and drawn to a larger scale, showing the drum and cage mounting, the section being taken substantially on the line 3—3 Fig. 2, looking in the direction of the arrows of said line;

Fig. 4 is a side elevation showing the basket;

Fig. 5 is a perspective view of the cage; and

Fig. 6 is a side elevation showing the closure and fastening means.

The movable parts of my improved apparatus for removing excess molten metal from articles, are carried on a pedestal 10 having a vertical bore 11 receiving fast therein a vertical main shaft 12 receiving loose thereon a miter gear 13 resting on the top of said pedestal.

A drive shaft 15 rotatable in horizontal bearings 16, 17 carries a miter pinion 18 meshing with said gear 13, whereby the gear is rotated.

A primary support such as a beam 20 is disposed diametric to said shaft 12 and fast on the top of said gear, and is provided with an inner bore loose on said shaft 12, and an adjustable counter poise 22 on one end.

A spur pinion 23 fast on said vertical shaft 12 above and engaging said beam, meshes with a large gear 24 rotatable on a stub shaft 25 fast in an end bore on the beam 26, whereby when the rotation of the drive shaft 15 causes the beam to revolve, the large gear 24 is given planetary movement.

A suitable secondary support such as a

circular table 28 fast on the top face of the large gear coaxial therewith carries a plurality of marginal standards 29 mounted fast on the margin of said table equal angles apart 5 and equal distances from the center.

A removable downwardly tapered drum or shield 30 is mounted on the table between opposite standards, and carries fast, on the outer face of its side wall, perforated brackets 31 10 received on the standards for positioning the drum with the drum bottom 32 on the table.

A cover 34 (Fig. 3) on said drum having a large central opening 35, has a down-turned flange 35' received over the drum and carrying bracket lugs 36 carried on the outer face of said flange and having vertical bores receiving the standards. Set screws 37 in radial threaded bores in said lugs respectively, engage said standards whereby the cover and 15 drum may be held in place, or removed when the set screws are loosened.

A pair of U-shaped elements 39, 40 having their lower yoke parts 39 crossed and secured together, form a cage or frame for the basket 25 41. The upper ends 42 of the arms 40 of said elements are out-turned and received in strap sockets 43 secured to the inner margin of the under face of said cover around said large opening, whereby the cage is rendered 30 removably secured under the cover. The perforated basket or bucket 41 is provided with a bail 42 whereby the basket with the molten metal covered articles therein may be disposed entirely within said cage and below 35 said opening 35.

Oppositely disposed perforated ears 45 are secured fast on the top face of said cover; and a closure 47 (Fig. 6) disposable in and over said large opening 35 is provided with 40 a handle 48 secured to its top face and having an extension 49 engageable in the perforation of one of said ears 45, while an outwardly spring pressed bolt 50 slidable in guide lugs 51, 52, and outwardly pressed by a spring 53 45 between the lug 52 and a collar 54 fast on the bolt, is engageable in the perforation of the other ear 45, whereby the closure may secure the basket and articles in the cage.

The operation of the apparatus is very 50 simple. With the closure and basket removed and the parts otherwise secured as in Figs. 1 and 3, the basket 41 of hot molten-metal-covered articles, are lowered into the cage; and the closure 47 is secured in place.

55 The table 28 and all parts thereon are then whirled for the desired length of time and at the desired speed, throwing the molten metal against the drum wall. After the articles have been sufficiently whirled, the closure 47 and the basket of articles are removed.

60 After repeating the process a number of times, it will be desirable to remove the congealed metal from the drum without long delaying the use of the apparatus. This is

done by loosening the set screws 37 and removing from the table all of the parts 30 to 42 immediately replacing the parts 30 to 40 with duplicate parts held in reserve, so as not to delay the machine, and immediately proceeding with the operation as first described. The congealed molten metal can be removed from the displaced drum at any convenient time while the machine is operating or at other times; and it can be easily arranged never to delay the operation for 70 75 75 prying off the congealed metal.

Thus it is seen that the drum accomplishes important functions.

First it collects the molten metal in the 80 drum 30 and prevents it from flying around inside the larger shield which usually surrounds such apparatus, such for instance, as the baffle 34 of the above second named patent, and thus prevents the particles of molten metal from being lodged on the machine and table 28. Heretofore it was necessary, after intervals of 20 to 50 basketfulls, to stop the machine and pry off the metal from the 85 table and other parts.

The drum is quickly detachable, and instead of taking time to pry off the sheets of thrown-off metal, the operator simply lifts off the drum, and substitutes another complete drum using the same closure as before, a sufficient number of drums being kept on hand to avoid all interruption of work.

Another important function of this drum is the retention of heat in and around the basket. In former machines the basket 100 whirling around off center at about 360 R. P. M. passes through, and creates, a considerable draft of cold air, which cools the articles sooner than is good for them. The drum 30 shields the articles from the cool 105 air currents which would be encountered were the drum not provided.

While herein is illustrated only planetary motion, rather than plain rotary, orbital, manual or other non-straight-line motion, the invention is not limited to planetary motion. Obviously the parts of the apparatus are made sufficiently heat-resistant where necessary.

I claim as my invention:

1. An apparatus for removing excess molten metal from articles, said apparatus comprising a support; means for imparting curvilinear movement to said support; a drum secured on the support; and a removable cage secured in said drum for holding a perforated basket within said drum.

2. An apparatus for removing excess molten metal from articles, said apparatus comprising a support; means for rotating said support; standards on said support; a removable drum on the support having a bottom, and side walls removably attached to the standards; a cover on said drum having a large central opening; releasable means to 120 125 130

hold the cover in place; a cage secured on the under face of said cover below said opening; a perforated basket disposable entirely within said cage; and a removable closure held over said large opening and basket.

5 3. An apparatus for removing excess molten metal from articles, said apparatus comprising a table; means for imparting orbital movement to said table; standards on the margin of said table; a removable drum on the table carrying perforated brackets received on the standards; a cover on the drum provided with a large central opening; brackets on the cover receiving the standards; 10 releasable means to hold the cover and drum in place; a basket-holding cage removably secured on the under face of said cover under said large opening; a perforated basket disposable entirely within said cage; and a removable closure held over said large opening and basket.

15 4. An apparatus for removing excess molten metal from articles, said apparatus comprising a table; means for imparting rotary movement to said table; standards on the margin of said table; a removable drum on the table; a cover on the drum; brackets on the cover receiving the standards; releasable means to hold the brackets in place; and a basket-holding cage removably secured 20 within said drum.

25 5. In combination, a rotary drum; a cover thereon having a large central opening; a pair of U-shaped elements having their lower yoke parts crossed and secured together, and having the upper ends of their arms outwardly and fastened to the inner margin of the under face of said cover around said large opening, thereby to form a cage or frame; a perforated basket provided with a bail whereby the basket with the molten-metal-covered articles therein, may be disposed entirely within said cage through said opening; and a closure for said large opening.

40 6. In combination, a rotary member; a circular table on said member; a plurality of marginal standards mounted fast on the margin of said table equal angles apart and equal 45 distances from the center; a removable drum mounted on the table between opposite standards, and carrying fast, on the lower part of its outer face, perforated brackets received on the standards for positioning the 50 drum; a cover on said drum having a large central opening and a down-turned flange received over the drum; bracket lugs carried on the outer face of said flange having vertical bores receiving the standards, and threaded bores radial to the vertical bores; set screws in said threaded bores respectively, whereby the cover and drum may be held in place, or removed when the set screws are loosened; and a basket-holding cage in said 55 drum.

7. An apparatus for removing excess molten metal from articles, said apparatus comprising a rotary support; a drum on the support; a cover on the drum having a central opening; releasable means to hold the drum and cover in place; a basket-holding cage secured under said large opening; a perforated basket movable through said opening into said cage; perforated ears fast on the top face of said cover on opposite sides of said central opening a closure disposable in and over said large opening and provided with a handle secured to its top face having an extension engageable in the perforation of one of said ears; and an outwardly sprung 70 pressed bolt engageable in the perforation of the other ear, whereby the closure may secure the basket and articles in the cage.

75 8. An apparatus for removing excess molten metal from articles, said apparatus comprising a pedestal having an axial bore therein and aligned horizontal bearings radial to said bore; a vertical main shaft carried fast to said bore; a miter gear loose on said shaft and resting on the top of said pedestal; a drive shaft rotatable in said horizontal bearings and carrying a miter pinion meshing with said gear, whereby the gear is rotated; a beam diametric to said shaft and fast on the top of said gear and provided with an inner bore loose on said shaft, an outer vertical end bore on one end, and an adjustable counter weight on the other; a spur pinion fast on said vertical shaft above said beam; a stub shaft fast in said end bore; a large pinion rotatable on said stub shaft and meshing with the spur pinion, whereby when the rotation of the drive shaft causes the beam to revolve the large pinion is given planetary movement; a table carried on said large gear; and means for carrying a perforated basket 80 on said table.

85 Signed at Garwood, in the county of Union and State of New Jersey, this ninth day of June, 1931, A. D.

90 DAVID TULLOCH.
